Primary Examiner — Sharon S Oum*Assistant Examiner* — Vanessa Martinez(74) *Attorney, Agent, or Firm* — Brooks Kushman P.C.(57) **CLAIM**

The ornamental design for a rear light as shown and described.

DESCRIPTION

FIG. 1 is a front perspective view thereof;

FIG. 2 is a front view thereof;

FIG. 3 is a top view thereof;

FIG. 4 is a bottom view thereof;

FIG. 5 is a left side view thereof;

FIG. 6 is a right side view thereof; and,

FIG. 7 is a rear perspective view thereof.

Portions of the article shown in broken lines form no part of the claimed design. Portions of the article shown in de-emphasized tones within broken line boundaries are not part of the claimed design.

1 Claim, 7 Drawing Sheets(56)
